UNITED STATES PATENT OFFICE.

AUGUST C. NIER AND CHARLES P. OLESON, OF ST. PAUL, MINNESOTA.

PRINTING DEVICE FOR BOOKBINDERS' PRESS-MARKS.

1,113,240.

Specification of Letters Patent.

Patented Oct. 13, 1914.

Application filed July 11, 1913. Serial No. 773,527.

To all whom it may concern:

Be it known that we, AUGUST C. NIER and CHARLES P. OLESON, citizens of the United States, residing at St. Paul, in the county of 5 Ramsey and State of Minnesota, have invented certain new and useful Improvements in Printing Devices for Bookbinders' Press-Marks, of which the following is a specification.

10 Our invention relates to improvements in printing devices for printing bookbinders' press marks upon the forms or signatures of a book while the same are being printed.

In bookbinding the order in which the 15 folded sets of sheets, or signatures as they are called, are to be arranged is indicated by a "signature number" which is printed upon each sheet as the same goes through the press, so that when the sheets are folded into 20 signatures for binding the signature number will be at the bottom of the outside page of the signature. The signatures are then assembled in the order indicated by the successive numbers. In order to avoid the 25 necessity of examining each of these numbers to see that the signatures are properly assembled, a press mark is sometimes placed upon the back fold of each signature at a distance from the head of the signature 30 which will vary according to the position the signature is to occupy in the bound volume, so that these marks will stand in regular gradations and form a broken line extending diagonally across the folded 35 back edges of the assembled signatures, and the absence of any mark or the presence of too many can be seen at a glance by a visual proof inspection of the back. These marks have been applied to the signatures 40 after the same have been printed and folded, but such subsequent application of the marks deprives them of any value in detecting inaccuracies or irregularities in printing or folding the sheets, and does not entirely 45 obviate the necessity of examining the successive signature numbers to make sure that all those of the same number have been collected into their own pile.

It is the object of the present invention to 50 provide improved means for accurately, quickly and conveniently printing these signature marks upon the signature sheets as the same are passed through the press and

before they have been folded. To this end we have devised means whereby the type 55 which is used for printing the mark does not have to be removed from the chase as the successive signatures are printed, but can be readily shifted and adjusted to the positions required for the succeeding signatures, and whereby the mark shall be so accurately placed as to enable the operator to detect errors in feeding the sheet through the press, or in folding the same, by inspection of the marks upon the folded back edges 60 of the signatures.

More particularly the invention consists in the construction, combination, and arrangement of parts hereinafter described and claimed.

In the accompanying drawings representing the preferred embodiment of the invention, Figure 1 is a perspective view of the improved type holder with some parts broken away; Fig. 2 is a longitudinal section through the middle of a fragment of the type holder; Fig. 3 is a perspective view of one of the sliding type; Figs. 4 and 5 are perspective views of modified forms of type ends which can be used for the second and 75 third rows of signatures, respectively; Fig. 6 is a detail of the spring pressed adjusting pin for the type; and Fig. 7 is a perspective view of a pile of signatures assembled for binding, showing press marks upon the back. 80

As shown in Fig. 1, the type holder comprises a bar 2 having along its longitudinal middle a slot 3 which is preferably widened or undercut at the base, so as to be T-shaped in section. Constructed to slide within this 90 slot is a type 4 with a widened or flanged base 5 adapted to fit within the undercut channel in the base of the slot. This type has a type face 6 of convenient length and width for the press mark to be printed. 95 Upon the face of the type holder are a succession of spacing marks 7 arranged at a distance apart approximately equal to the length of the type face 6. The spaces between the spacing marks are numbered consecutively from "One" up as a guide for setting the type. The type is held in adjusted positions, so that its face will register with any of the numbered spaces upon the holder, by means of a pin 8 which extends 100 down through the type and is adapted to fit

into any one of the holes 9 in the holder. It will be seen that type is notched or cut away at the place where the pin passes through it, so that the head 19 of the pin 5 will lie below the printing face of the type. The pin is held normally in down thrust position by means of a spring 10, which bears at one end against a shoulder 11 in the holder and at the other end against a shoulder 12 on the pin. The holes 9 are equal in 10 number to the spaces upon the face of the holder, and are so positioned that the type face will register with one of the numbered spaces whenever the pin fits into a hole. The 15 holder has at one end a spur headed extension screw 13 whereby it can be made to fit the "furniture" of the chase.

In use, the type holder is placed within the frame or chase which carries the type 20 for printing the signature sheet, and made fast therein by means of the screw 13. The pin 8 of the type is then drawn up against the pressure of its spring until it emerges from the hole 9 and clears the bottom of 25 the slot, thus leaving the type free to move. The type is then moved along the slot until its face registers with the space bearing the same number as the signature number 30 of the sheet to be printed. If the signature is to be placed at the beginning of the book, the type will be adjusted in the slot so that its face will register with the space numbered "One" on the holder. When the type has reached this position, the pin, if released, 35 will spring down into the hole provided for the space numbered "One", thereby locking the type firmly in the position at which it has been set. The type face for the press mark can then be inked with the other type 40 in the chase, and, as the sheets A are passed through the press, will print at the line of fold a mark 14 of the same length as the type face, or, in other words, of the same length as one of the spaces upon the holder. 45 When the next succeeding signature sheets are to be printed, the type will be moved back one space so that its face will register with the space numbered "Two", and the second sheets will be printed as above 50 described.

The holder is made preferably of the same length as the printed page, so that the press marks upon the backs of the signatures will extend in a continuous, but broken, line from 55 the top of the volume to the bottom thereof. If, now, more signatures are required to complete the book, it will be necessary to begin over again at the top for a second pile of signatures. In order to distinguish these 60 signatures from those first placed, a type may be used which has two separated face parts 15, as illustrated in Fig. 4. If a third pile or row of signatures becomes necessary, a type may be used which has three separated face parts 16, as shown in Fig. 5. In

this way it is possible to distinguish whether the signature belongs to the second or third pile, it being impossible to distinguish merely by the position of the mark with reference to the top of the page. In the 70 drawings, 17 indicates the press mark made by the use of the two-faced type shown in Fig. 4, while 18 indicates the press mark made by the use of the three-faced type shown in Fig. 5. 75

We claim as our invention:

1. A device for printing a bookbinder's press mark comprising a type holding bar longitudinally slotted to receive a type and formed with a succession of holes equi-distant from one another, a type movable in said slot and having a hole in position to register with the successive holes in the type bar as the type is moved along the bar, and an adjusting pin movably held in the registering holes whereby to lock the type against longitudinal movement in the slot. 80

2. A device for printing a bookbinder's press mark comprising a type holding bar longitudinally slotted to receive a type and formed at the bottom of the slot with a succession of holes, a type movable in the slot and formed with a hole, and an adjusting pin extending through the hole in the type and into one of the holes in the bar whereby to lock the type against longitudinal movement. 90

3. A device for printing a bookbinder's press mark comprising a type holding bar longitudinally slotted to receive a type and formed at the bottom of the slot with a succession of holes, a type movable in the slot, and a spring controlled adjusting pin extending through the type and adapted to enter the holes in the bar. 100

4. A device for printing a bookbinder's press mark comprising a type holding bar longitudinally slotted to receive a type, said bar having its face marked off into numbered spaces of equal length and being formed at the bottom with a succession of holes equi-distant from one another, a type movable in said slot, and a spring pressed adjusting pin extending through the type and adapted to enter the holes in the bar, the face of the type corresponding in length to the several spaces on the face of the bar. 110

5. A device for printing a bookbinder's press mark comprising a type holding bar marked off into numbered spaces of equal length and formed with a succession of correspondingly spaced holes, a type movable longitudinally of said bar, and an adjusting pin extending through said type and into the registering hole in the bar, whereby 120 to lock the type against longitudinal movement. 125

6. A device for printing a bookbinder's press mark comprising a type holding bar longitudinally slotted to receive a type and 130

formed at the bottom of the slot with a succession of holes, a type movable in the slot and formed at one end with a depressed portion and an adjusting pin extending movably through said depressed portion and into the holes in the bar with its head below the face of the type, for the purpose set forth.

In testimony whereof we affix our signatures in presence of two witnesses.
